Des. 209,440
Patented Nov. 28, 1967

209,440

CHEMICAL FEEDING UNIT FOR SWIMMING POOLS

Thomas E. Schneider, Jr., Atlanta, Ga., assignor to
Tesco Chemicals, Inc., Atlanta, Ga., a corporation
of Georgia

Filed Nov. 17, 1966, Ser. No. 4,727

Term of patent 14 years

(Cl. D91—1)

Fig. 5

Fig. 4

FIG. 1 is a front perspective view of a chemical feeding unit for swimming pools showing my new design;

FIG. 2 is a front perspective view of a modified embodiment of the chemical feeding unit for swimming pools disclosed in FIG. 1; and

FIG. 3 is a top view of the chemical feeding unit for swimming pools disclosed in FIG. 1.

FIGURE 4 is a rear perspective view of the embodiment shown in FIG. 1; and

FIGURE 5 is a rear perspective view of the embodiment shown in FIG. 2.

I claim:

The ornamental design for a chemical feeding unit for swimming pools, as shown and described.
